UNITED STATES PATENT OFFICE.

LEROY W. BALDWIN, OF NEW YORK, N. Y.

DESIGN FOR A DIAL-FACE.

SPECIFICATION forming part of Design No. 32,684, dated May 22, 1900.

Application filed April 26, 1900. Serial No. 14,511. Term of patent 14 years.

To all whom it may concern:

Be it known that I, LEROY W. BALDWIN, a citizen of the United States, residing at New York, in the county of New York and State of New York, have invented and produced a new and original Design for Dial-Faces, of which the following is a specification, reference being had to the accompanying drawing, forming part thereof.

10 My invention relates to dials or dial-faces in general, and is more specifically intended for use on the dials of automatic weighing-machines for the purpose of rendering the same attractive to the eye and presenting different sections of the dial-face with different degrees of prominence.

The drawing represents a face view of a weighing-machine dial, showing my new design.

15 As shown in the drawing, the leading fea-

ture of my design is a series of rectangular panels A A', &c., so combined as to form a larger panel B and located all on one side of a line passing through the center of the dial.

The face of the dial and the outlines of the 25 panels should be in contrasting colors.

It is apparent that this design is also applicable to timepieces and other instruments having dial-faces.

Having therefore described my invention, 30 what I claim as new, and desire to protect by Letters Patent, is—

The design for a dial-face as herein shown and described.

Signed at New York, N. Y., April 24, 1900. 35

LEROY W. BALDWIN.
